GEORGE B. SCHEFFBEY, OF WEEHAWKEN, NEW JERSEY, ASSIGNOR TO WILLIAM LUNSFORD LONG, OF ROANOKE RAPIDS, NORTH CAROLINA.

LABELING MECHANISM.

Application filed November 19, 1925. Serial No. 70,029.

My invention relates to mechanism for rapidly and economically applying labels to articles.

In the exemplifying embodiment here shown and described, the machine is particularly adapted for applying end labels to relatively thin, flat, oblong articles such as cloth boards; but evidently the mechanism is adapted or adaptable for applying labels or similar paper strips or sheets to other more or less similar articles.

The general object of the invention is to provide simple and inexpensive mechanism which is largely, although not necessarily entirely, automatic in operation, and which may be operated by practically unskilled labor to rapidly and economically label articles such as cloth boards on a high-production basis.

To this end the mechanism embodying the invention as here represented includes a label holder, an appliance such as a rotary turret provided with one or more labeling pockets or similar devices, means for operating the turret to position labels successively in relation to the pockets, adhesively condition them, and present them for application to articles such as cloth boards, which are moved into co-operation with the pockets or similar turret devices.

In some cases the manipulation or "feed" of the articles might be automatic, but for the sake of simplicity and economy the present specific mechanism is designed for hand-presentation of the cloth boards or similar articles to the turret pockets or similar label applying devices.

The characteristics and advantages of the invention are further sufficiently explained in connection with the following detail description of the accompanying drawings, which show one representative embodiment of the invention. After considering this example, skilled persons will understand that many variations may be made, and I contemplate the employment of any structures that are properly within the scope of the appended claims.

In the drawings:

Fig. 1 is a front elevation of a machine embodying the invention in one form, with some parts broken away.

Fig. 2 is a vertical section at 2—2, Fig. 1.

Fig. 3 is a detail in section at 3—3, Fig. 2, of one of the label-applying devices.

Fig. 4 is a perspective view of one end of a labeled cloth board.

Fig. 5 is an elevation at the right of Fig. 1.

Fig. 6 is an enlarged detail section at 60—6, Fig. 5.

Fig. 7 is a sectional detail at 7—7, Fig. 6.

The machine is built on or around a frame comprising end uprights or standards 1 connected by suitable cross members 65 such as 2.

A rotary turret 3 has stub shafts 4 revolvably mounted in bearings in rock arms 4^a, which are pivotally mounted at 4^b and adjustable stop nuts 4^c maintain the arms in 70 adjustable upright position and resiliently cushion the turret to permit it to yield somewhat toward the right as viewed in Figs. 2 and 5. A magazine or holder 6 for a stack of labels L is mounted above the 75 turret, usually in tilted or oblique relation thereto. Gluing mechanism 7 is located below the turret. At the front or operator's side of the machine brackets 8 extend outward and are provided with a table, or narrow ledges 11, to support an article such as a cloth board B and to properly position the board laterally as it is advanced to co-operate with the label-applying means.

The turret has one or a plurality of labeling pockets 15. Conveniently, as in the present example, three of these pockets may be provided, equally spaced. At the outside of each pocket two part-cylindrical

label-receiving segments 16 and 17 are provided, with their confronting edges separated by a space 18 of substantially greater width than the thickness of the cloth board to be labeled. Within each pocket near the edges of the segments 16 and 17 are label 95 pressing rolls 19 rotatably mounted in spring supports 20. Each leading label segment 17 has a longitudinal, spaced series of suction holes 21 communicating with a turret channel 22 parallel to the rotative 100 axis. These channels are closed at one end and at the other end (at the right in Fig. 1) they co-operate with a part circular channel 23 formed in a stationary circular valve plate 24 concentric with the turret 105 axis. Cam devices are provided for operating the label magazine, and for structural convenience these may be formed on cam plates 26 and 27 separate from the turret and concentric therewith and secured 110

against it at opposite ends. Thus cam plate 27 as shown in Fig. 6 is interposed between the end of the turret and valve plate 24 and is bored to provide air passages 28 in line with the longitudinal passages 22 of the turret.

At one end of the air channel 23, which is the end of the channel first encountered by an air channel 22 or its extension 28, a valve cylinder 30 is provided to receive a cylindrical or plug valve 31, normally pressed inward to closed position by a spring 32. The valve thus normally acts to close the channel 23 or to prevent the application of suction to the channels 22 when they first come into co-operation with the part-circular channel 23, as later more fully explained. The valve is operated by an angular or beveled member 33 acting between circular flanges 34 on the valve stem. The member 33 is carried by an arm 35, and this arm is connected to a movable part of the label magazine, as later explained.

The frame members 1 are provided with inclined brackets 40, and on these a plate or magazine sub-base 41 is mounted. The sub-base 41 may be slidingly adjusted and secured on frame members 40 in any known or suitable way for the bodily adjustment of the magazine in relation to the turret. The plate or sub-base 41 has bearings in brackets 42, to receive trunnions 43 connected to the magazine base 44, which is thus pivotally mounted in relation to the sub-base 41 and the turret. The base plate 44 also has studs 46 which run on the peripheries of cam discs 47 formed as flanges on the cam plates 26 and 27 above mentioned. Each of these cam discs has peripheral notches 48 corresponding in location to the centers of the labeling pockets 15. Normally the magazine with its base plate 44 is held in elevated position by the rollers 46 running on the circular peripheries of the cam discs 47; but whenever one of the pockets 15 is positioned directly below the magazine to receive a label the rolls 46 drop into two of the aligned notches 48, and the magazine drops to bring the label close to the label-receiving segments 16 and 17.

The magazine proper comprises a rear upright guide plate 50 provided with side flanges 51 and secured to brackets 52 which may be adjustable longitudinally on the base 44. The rearward or lower portions of the label rest against plate 50 and are prevented from lateral displacement by the side flanges 51. The upper or forward portion of the stack is supported by spaced blades 55 having narrow bottom extensions 56 bent at right angles and lying under the stack. The blades 55 are secured to a rail 57, and this is supported by brackets 58, which may also be adjustable on the base 44, so that by adjustment of the brackets 52 and 58 labels

of any size within a considerable range may be properly supported. The lower or rearward portion of the stack bottom is supported by short spaced blades or fingers 60 projecting from the bottom of the back 70 plate 50.

The valve operating arm 35 above referred to is secured to the magazine base 44 at 65, and the valve is therefore actuated by the downward movement of the magazine as a label pocket is positioned below the magazine, as shown in Fig. 2.

The gluing mechanism includes a main glue roll 70 carried by a shaft 71, which may also be the main drive shaft of the machine, and for that purpose is provided with a drive pulley 71^a driven by a belt 72 from any suitable source of power, or an individual motor drive or any other suitable driving means may be provided.

Preferably the drive pulley is keyed to the shaft so that the glue roll turns continuously. The periphery of the glue roll is positioned to engage with proper pressure, labels carried by the label segments 16 and 17, and to insure proper contact, and also to provide for different thicknesses of labels the turret may be moved toward or from the glue roll by adjustment of the nuts 4^c above referred to.

The glue roll is in contact with a dipper roll 72 carried by a shaft 74 having bearings in arms 75 pivoted at 76. Screws 77 resting on frame lugs 78 provide for proper adjustment of the dipper roll in relation to the main roll 70. The dipper roll runs in a body of glue in a glue trough 79. The dipper roll is driven by a gear 80 engaging a pinion 81 fixed on the main shaft 71.

The turret is intermittently driven from shaft 71 by any known or suitable single-revolution clutch, such as the pin or dog clutch 85 on shaft 71. With this clutch is associated a pinion 86 engaging a gear 87 on turret shaft 4, the ratio of these gears being one to three in accordance with the triplicate arrangement of labeling pockets. The clutch is controlled by the beveled end 88 of a lever 89 fulcrumed at 76, and the lever is controlled by a link 90 under the control of the operator, for example, by means of a pedal (not shown) located near the floor and convenient to the operator as he stands in front of the machine or at the left in Fig. 2. Single revolution clutches of this type are well known and the details will therefore not be described. Whenever the pedal is depressed link 90 acts to withdraw the member 88 of lever 89 and causes engagement of the clutch which then makes one revolution and stops. In the revolution of the clutch, pinion 86 turns gear 87 and the turret one-third revolution.

Any known or suitable air exhauster may be employed to provide the required "suc-

tion" for label receiving and holding operations. Conveniently a rotary exhauster 100 is provided, driven by a pinion 101 on its shaft 102 engaging a large gear 103 on the main or drive shaft 71. The intake of the exhauster is connected by a flexible tube 105 to a nipple 106 in communication with the part circular channel 23.

The turret 3 rotates clockwise as viewed in Figs. 2 or 5. As one of the labeling pockets 20 approaches a position below the magazine holding labels L, the cam notches 48 corresponding to the pocket approach the rollers 46 and the rollers begin to drop into the notch with concurrent depression of the magazine and its base plate 44. One of the longitudinal air passages 22 now commences to come into registry with one end of the part circular channel 23, but at this time the plug valve 31 is in its inward or closed position, so that its inner end confronts the end of the passage 22 or 28 and prevents the application of suction. As the cam rollers drop farther into the notches, the beveled or angular end 33 of arm 35 acts upon the valve and finally as the rollers drop to the bottoms of the notches and the magazine is fully depressed to the position of Fig. 2, the valve is opened and suction is quite suddenly applied to the passages 23, 28, 22 and the radial passages 21. This suction or vacuum effect draws the rearward end of the bottom label out from above the support fingers 62 and causes the rearward part of the label to adhere firmly to the label segments 17. The single revolution clutch 85 is adjusted or positioned so that the clutch releases and the turret is stopped at this moment, and the table or ledges 11 provided for the support of the cloth board B are positioned so that the second labeling pocket in advance of the one that has just received a label is now substantially in line with the ledges. After a cloth board has been positioned and manipulated to receive a label and removed, the operator depresses the pedal connected to link 90 to restart the turret.

In the first part of the turret movement the label previously grasped on holding segment 17 is pulled from the bottom of the stack and away from the supporting fingers 56 and trails behind the segment 17 or lies upon the rear segment 16. When this label and its pocket reach the lower right-hand position of Fig. 2, the turret is again stopped while a label is supplied to the upward label segment 17 by the magazine and one end of another cloth board is labeled. The turret is then restarted and the label at the lower right hand position is carried past the glue roll 70 and its outer face is covered with glue. The label is then presented at label applying position, at the left, Fig. 2, with the label stretched across the two label holding faces 16 and 17. The part-circular air chan-

nel 23 is of such length that the passage 22, 28, corresponding to the label holding segment at labeling position passes away from the end of the part-circular channel at or about the time that the turret comes to rest. The label is then held by residual suction in the air passages, but this suction is insufficient to considerably resist sliding movement of the label away from the holding surface 17 when the cloth board is applied. The attendant places a cloth board B on the ledges 11 and shoves one end of it in toward the turret pocket. The end of the board strikes the mid-portion of the label and bends and presses the label inward between the affixing rolls 19, which wipe and press the glued surfaces of the label upon the upper and lower surfaces of the board. The inner end of the pocket may be so positioned as to properly limit the inward movement of the board with regard to the length of the label portions, or other stop means may be provided. The cloth board is then withdrawn, carrying with it the affixed label L as shown in Fig. 4. The operator then restarts the turret, reverses the cloth board and labels the other end, and so on.

In some cases the clutch or "stop" action may be omitted and intermittent driving mechanism provided, which gives a sufficient dwell of the turret to permit the label affixing operation; but usually the clutch or equivalent stop mechanism is desirable in order to give sufficient, arbitrarily regulated time for the manipulation of the cloth board.

I claim:

1. Labeling mechanism for applying labels to relatively thin, flat articles such as cloth boards, comprising a rotary turret, a labeling pocket in the periphery thereof, formations at opposite sides of the pocket mouth to receive and hold a label extending across said mouth, and means within the pocket for folding and applying a label across the edge and upon opposite faces of the article as the same is advanced through the pocket mouth into the pocket and then retracted.

2. Labeling mechanism for applying labels to relatively thin, flat articles such as cloth boards, comprising a rotary turret, a labeling pocket in the periphery thereof, formations at opposite sides of the pocket mouth to receive and hold a label extending across said mouth, means within the pocket for folding and applying a label across the edge and upon opposite faces of the article as the same is advanced through the pocket mouth into the pocket and then retracted, a label stack holder and means for moving the holder in relation to turret movements to apply a label to the pocket label-receiving formations.

3. Labeling mechanism for applying labels to relatively thin, flat articles such

as cloth boards, comprising a rotary turret, a labeling pocket in the periphery thereof, formations at opposite sides of the pocket mouth to receive and hold a label extending across said mouth, one of said label receiving formations having suction means to grasp and hold the leading margin of the label, and means within the pocket for folding and applying a label across the edge and upon opposite faces of the article as the same is advanced through the pocket mouth into the pocket and then retracted.

4. Labeling mechanism for applying labels to relatively thin, flat articles such as cloth boards, comprising a rotary turret, a labeling pocket in the periphery thereof, formations at opposite sides of the pocket mouth to receive and hold a label extending across said mouth, means for applying adhesive to the outer face of the label as it moves toward labeling position, and means within the pocket for folding and applying a label across the edge and upon opposite faces of the article as the same is advanced through the pocket mouth into the pocket and then retracted.

5. Labeling mechanism for applying labels to relatively thin, flat articles such as cloth boards, comprising a rotary turret, a labeling pocket in the periphery thereof, formations at opposite sides of the pocket mouth to receive and hold a label extending across said mouth, means within the pocket for folding and applying a label across the edge and upon opposite faces of the article as the same is advanced through the pocket mouth into the pocket and then retracted, and means at a labeling station for supporting and directing the article for movement to, into and from the labeling pocket.

6. A labeling machine of the class described, comprising a rotary turret having in its periphery a plurality of spaced labeling pockets, each pocket having at opposite sides of the mouth thereof, label receiving faces, one of said faces having a suction aperture to grasp and hold the leading margin of a label which extends across said mouth and lies upon the other of said label receiving faces, opposite applying and pressing devices yieldably mounted within each pocket for applying a label across the end of an article such as a cloth board and upon opposite side faces thereof as the article is advanced through the turret mouth past said applying devices and then withdrawn, and article supporting and guiding means arranged to direct the movement of articles to, into and from the successive labeling pockets.

7. A labeling machine of the class described, comprising a rotary turret having in its periphery a plurality of spaced labeling pockets, each pocket having at opposite sides of the mouth thereof, label receiving

faces, one of said faces having a suction aperture to grasp and hold the leading margin of a label which extends across said mouth and lies upon the other of said label receiving faces, opposite applying and pressing devices yieldably mounted within each pocket for applying a label across the end of an article such as a cloth board and upon opposite side faces thereof as the article is advanced through the turret mouth past said applying devices and then withdrawn, adhesive applying means including a roll for applying adhesive to the outer faces of successive labels passed in contact with the roll by the pocket label receiving faces, and article supporting and guiding means arranged to direct the movement of articles to, into and from the successive labeling pockets.

8. A labeling machine of the class described comprising a rotary turret having in its periphery a plurality of spaced labeling pockets, each pocket having at opposite sides of the mouth thereof, label receiving faces, one of said faces having suction means to grasp and hold the leading margin of a label which extends across said mouth and lies upon the other of said label receiving faces, opposite applying and pressing rolls and spring supports therefor within each pocket for applying a label across the end of an article such as a cloth board and upon opposite side faces thereof as the article is advanced through the turret mouth past said applying devices and then withdrawn, and article supporting and guiding means arranged at a labeling station to direct the movement of an article to, into and from a labeling pocket there positioned.

9. Labeling mechanism comprising a turret, one or more labeling pockets therein, label applying means associated with the pockets, label-holding segments adjacent the pockets, and suction mechanism comprising air passages communicating with one of the segments of each pocket, a main passage therefor, and a relatively stationary arcuate passage co-operating with said main passage to control the suction effect.

10. Labeling mechanism comprising a turret, one or more labeling pockets therein, label applying means associated with the pockets, label-holding segments adjacent the pockets, and suction mechanism comprising air passages communicating with one of the segments of each pocket, a main passage therefor, a relatively stationary arcuate passage co-operating with said main passage to control the suction effect, and a valve at the interior end of said arcuate passage to cut off suction application when said main passage is first positioned in relation to the arcuate passage.

11. Labeling mechanism comprising a turret, one or more labeling pockets therein,

label applying means associated with the pockets, label-holding segments adjacent the pockets, and suction mechanism comprising air passages communicating with one of the segments of each pocket, a main passage therefor, a relatively stationary arcuate passage co-operating with said main passage to control the suction effect, and a label magazine arranged to present labels adjacent the label segments at one turret position.

12. Labeling mechanism comprising a turret, one or more labeling pockets therein, label applying means associated with the pockets, label-holding segments adjacent the pockets, and suction mechanism comprising air passages communicating with one of the segments of each pocket, a main passage

therefor, a relatively stationary arcuate passage co-operating with the said main passage to control the suction effect, a valve at 20 the interior end of said arcuate passage to cut off suction application when said main passage is first positioned in relation to the arcuate passage, a label magazine movably mounted in relation to the turret to supply 25 labels to the label segments, means operated by turret movement for moving the magazine toward and from the turret, and means operated by magazine movement to control said valve.

Signed at New York city in the county of New York and State of New York this 16th day of Novbr. A. D. 1925.

GEORGE B. SCHEFFEY.
